Nostalgia Two-Speed Electric Coca-Cola Limited Edition Milkshake Maker . Date First Available on Amazon.com Jun. 14, 2016 <https://www.amazon.com/Nostalgia-MLKS100COKE-Coca-Cola-Two-Speed-Milkshake/dp/B01H1UXEPO/ref> (Year: 2016).*Primary Examiner — Ricky Pham(74) *Attorney, Agent, or Firm* — Quarles & Brady LLP(57) **CLAIM**

The ornamental design for a mixer, as shown and described.

DESCRIPTION

FIG. 1 is a perspective view of a front, top, and right side of an ornamental design for a mixer;

FIG. 2 is a front elevational view of the mixer of FIG. 1; FIG. 3 is a right side elevational view of the mixer of FIG. 1;

FIG. 4 is a left side elevational view of the mixer of FIG. 1; FIG. 5 is a rear elevational view of the mixer of FIG. 1; FIG. 6 is a top plan view of the mixer of FIG. 1; FIG. 7 is a bottom plan view of the mixer of FIG. 1; and, FIG. 8 is a perspective view of a front, top, and left side of the mixer of FIG. 1.

The dash-dash-dash lines are included for the purpose of illustrating portions of the mixer that form no part of the claimed design. The dash-dot-dash lines are included for the purpose of illustrating a boundary line, and form no part of the claimed design.
